UNITED STATES PATENT OFFICE

96,607

DESIGN FOR A HOT WATER BOTTLE STOPPER

Albert Karn, Richmond Hill, N. Y., assignor to
Scovill Manufacturing Company, Waterbury,
Conn., a corporation of Connecticut

Application May 17, 1935, Serial No. 56,885

Term of patent 14 years

To all whom it may concern:

Be it known that I, Albert Karn, a citizen of the United States of America, residing in Richmond Hill, in the county of Queens and State of New York, have invented a new, original, and ornamental Design for a Hot Water Bottle Stopper, of which the following is a specification, reference being had to the accompanying drawing, forming part thereof.

In the drawing,—

Figure 1 is a front elevation of a hot water bottle stopper showing my new design, the screw threaded portion of the stopper being shown in dot and dash lines;

Fig. 2 is a top plan view of my design;

Fig. 3 is a section taken along the plane of the line 3—3 of Fig. 1.

The dominant feature of my design resides in the portions thereof shown in full lines.

I claim:

The ornamental design for a hot water bottle stopper as shown and described.

In witness whereof, I have hereunto signed my name.

ALBERT KARN.
